UNITED STATES PATENT OFFICE

ALBERT E. R. SPEIDEL, OF EDGEWOOD, RHODE ISLAND, ASSIGNOR TO SPEIDEL CORPORATION, A CORPORATION OF RHODE ISLAND

DESIGN FOR AVIATOR'S EMBLEM OR SIMILAR ARTICLE

Application filed December 12, 1932. Serial No. 46,442. Term of patent 7 years.

To all whom it may concern:

Be it known that I, ALBERT E. R. SPEIDEL, a citizen of the United States of America, residing in Edgewood, county of Providence, State of Rhode Island, have invented a new, original, and ornamental Design for an Aviator's Emblem or Similar Article, of which the following is a specification, reference being had to the accompanying drawing, forming a part thereof.

Fig. 1 is a front view of an aviator's emblem or similar article, showing my new design; Fig. 2 is a top plan view of the same.

I claim:

The ornamental design for an aviator's emblem or similar article substantially as shown.

ALBERT E. R. SPEIDEL.
